UNITED STATES PATENT OFFICE.

CHARLES HENRY ATKINS, OF SPRINGFIELD, MASSACHUSETTS.

WARP STOP-MOTION FOR WIRE-WEAVING LOOMS.

No. 858,139.

Specification of Letters Patent.

Patented June 25, 1907.

Application filed July 31, 1906. Serial No. 328,611.

To all whom it may concern:

Be it known that I, CHARLES HENRY ATKINS, a citizen of the United States of America, and a resident of Springfield, in the county of Hampden and State of Massachusetts, have invented certain new and useful Improvements in Warp Stop - Motion for Wire-Weaving Looms, of which the following is a full, clear, and exact description.

This invention relates to a warp stop motion especially for looms for weaving wire or for the weaving of any textile fabric in which essentially metallic warps are employed.

An object of the invention is to provide means whereby upon the breakage of one of the series of warp wires running through the loom advantage may be taken of the metallic and current conducting quality of the broken warp wire for the establishment of an electric circuit which controls the stop motion.

Another object is to provide a magnetic brake in conjunction with the stop motion of the loom, the same to become effective immediately the loom driving mechanism is disconnected to instantaneously stop part of the loom which may be running under momentum. And another object is to provide a stop motion with provisions whereby the loom will be stopped, irrespective of where the lay and other moving parts may be at the time of breakage of a warp wire, only when the lay and such other moving parts are in some given position as may be predetermined and provided for; such predetermined position of stoppage generally and preferably being with the lay in its most rearward position.

The invention consists in apparatus and parts in arrangement or organization, as exemplified in the accompanying drawings, described in the following specification and covered in and by the claims.

In the accompanying drawings,—Figure 1 is a side elevation of sufficient of a wire weaving loom to show the combination therewith of the present improved electrical stop motion, the same being in large measure illustrated in a diagrammatical manner. This view shows the lay as in its most forward or beating-up position. Fig. 2 is a view substantially like Fig. 1 but showing the lay as in its most rearward position, and at a time only when the stop motion, as illustrated in these views, can be operative to

stop the running of the loom. Fig. 2^a is a sectional elevation as taken on the line 2^a—2^a, Fig. 2, for especially showing a face view of the controller actuating cam herein- 65 after particularly referred to. Fig. 3 is a diagrammatic illustration of the stop motion comprising the components essentially included in the preceding figure, but with the capability of stopping the loom instantly on a 65 warp break, irrespective of where the moving parts of the loom at that time may be. Fig. 4 is a sectional elevation of the lay of the loom showing the location thereon of a number of insulated pieces hereinafter par- 70 ticularly referred to.

The same or similar characters denote the same or similar parts in all of the views.

In the drawings,—A represents a shaft which may be properly regarded as the driving shaft for actuating the movable parts of the loom, the same being mounted in journal brackets *a a* understood as mounted on the loom frame B, and capable, in addition to its free rotary motion, of a slight endwise 80 shifting movement in its journals. This shaft A by belt *b* running around a pulley *b*² thereon drives a pulley C on another shaft D which is understood as having connections, by mediums of transmission most of which 85 are not shown, with the various "motions" of the loom.

E represents the primary driver for the driving shaft A loosely mounted and movable relatively to such shaft and adapted by a 90 magnetic connecting device, when the latter is energized, to be connected with the shaft. The driver E is shown as in the form of a pulley and understood as loosely rotatable about an intermediate portion of the said 95 shaft A, and having a clutch magnet F set within the face thereof and adjacent a disk G which is keyed to and revolves in unison with the shaft A. Supported adjacent and at the side of the disk G opposite from the pulley carrying the clutch magnet F is a 100 brake magnet H.

J represents a dynamo or other suitable type of generator, oppositely connected to which are conductors *c* and *c*², the former running from the generator to a collector ring *d* insulated from and surrounding the shaft A, and wired to one end of the coil of the clutch magnet F, while the conductor *c*² oppositely connected with the generator runs to a contact *e* and through the switch *f*; when the latter is closed, to another contact *i* with which

the conductor c^2 has connection, and runs to the other collector ring d^2 adjacent the one d which is wired to the other end of the clutch magnet coil F . A circuit for the brake magnet coil, including the dynamo, may, for instance, be constituted by a wire g having connection with one end of the brake magnet coil and with the wire c connected with the dynamo,—forming part of the clutch magnet 5 circuit, and by the wire g^2 running from the other end of the brake magnet coil to the contact i^2 opposite the one i to be in electrical connection, when the switch f is in the position shown in Figs. 1 and 2 with the same wire c^2 which has connection with the dynamo and also forms part of the clutch magnet 10 circuit.

L represents a metallic piece extending transversely of the loom, insulated from all 20 other metallic parts of the loom and having a position adjacent the multiplicity of longitudinally extending warp wires x to be, with great certainty or probability, contacted against by any warp wire, running from the 25 warp beam to the made cloth near the breast beam, which may become severed. This metallic piece is represented in Fig. 3 as made in the form of a metallic strip understood as extending the whole length of the metallic 30 lay beam M and by the insulation h absolutely out of metallic or electrical connection with the lay beam as well as all other parts of the loom.

N represents an electro magnet for controlling the aforementioned switch and consequently the cut-out for the magnetic clutch and magnetic brake circuits, such switch operating and in conjunction with the contacts e and i, i^2 . The part j , which is the armature of 35 the electro magnet N is pivotally mounted at j^2 and has a catch shoulder j^3 for engaging the switch f and holding it in the position shown by full lines Fig. 3, and by dotted lines Figs. 1 and 2, against the action of the switch 40 spring j^2 ; and the spring j^4 holds the armature in its switch engaging position and away from the electro magnet,—the same to be overpowered, however, by the attraction of the electro magnet when the same becomes 45 energized on the completion or closing of the electro magnet circuit by a metallic warp wire coming to contact against said insulated transversely extending metallic piece L . One 50 of the conductors k of the electro magnet circuit has connection with one end of the electro magnet coil and with the transverse insulated piece or strip L . The circuit conductor k^2 has connection with the other end of the electro magnet coil, and as an instance, 55 and for the purpose of present illustration, with the metallic lay beam M .

K represents a battery or other generator connected in the electro magnet circuit.

It is to be stated, as a practical and important fact, of which especial cognizance is to

be taken, that the metallic part of the loom, as for instance, the lay beam M , is one in which there is to be at all times a metallic or electrical connection with the warp wires, it being remembered that the warp wires are wound around an iron or steel warp beam 70 mounted in metal journal bearings in the iron loom frame, in which frame the metal pivots of the metal lay sword are supported; and the warp wires, moreover, are in metallic 75 contact with the breast beam and take-up beam of the loom; and hence, no matter at what place in its length between the warp beam and cloth line a warp wire severed, it will, by coming to contact against the insulated transverse metallic piece, cause a closing 80 of the electro magnet circuit, and an energizing of the electro magnet, a shifting of the switch f , thereby cutting out the direct magnetic clutch circuit, leaving the driver 85 disconnected from the driving shaft, and at the same time establishing the circuit, including the dynamo and brake magnet, for rendering the brake operable to quickly overcome the momentum of the driving shaft. 90

It will be explained that when the magnet coil F is energized by the current from the dynamo in the circuit through such magnet coil, the metallic portions of the iron pulley E are constituted a powerful magnet which 95 the disk G on the driving shaft a will be attracted to, the slight “end shake” of the shaft permitting; it being similarly the case that when the circuit conductors, including 100 the brake magnet coil, are energized by being in circuit with the dynamo, the iron in the circular metallic body within which the brake magnet is embodied, becomes a powerful electro magnet to which will be attracted, in the opposite direction, the disk G 105 on the slightly endwise shiftable driving shaft A .

The electro magnetic and partially mechanical warp stop motion so far as has been described with the pointing out of the constituents thereof, is one of a simple character, 110 operable upon the severing of a warp wire to instantaneously absolutely cut out the dynamo current from the magnetic clutch and establish the dynamo current through the 115 magnet brake to instantly stop the loom, irrespective of the positions in which the moving loom parts may be at the instant of the breaking of the warp; and from the substantially diagrammatic view, Fig. 3, the essentials 120 comprised in the stop motion as constituted to the extent of means thus far described, may be identified, and the operation thereof understood. And in connection with the said Fig. 3, it will be seen that the 125 clutch magnet circuit is closed and the magnetic brake circuit open; the switch f connecting the contact e with the contact i being held in such position by the electro magnet armature j . Now, assuming that the 130

warp wire, as represented by the dotted line x^2 in said Fig. 3, becomes severed and falls onto the transversely extending metallic piece L, it will be apparent that the electro magnet circuit becomes closed or established, the current passing from the battery K by way of wire k^2 to and through the electro magnet coil, thence by wire k to the said metallic piece L, thence by way of the warp wire through the warp-beam, loop-frame, and metallic connection, as diagrammatically illustrated by the dotted line y , to the metallic lay beam M having, by the wiring or metallic connection k^2 , a return course to the battery.

In some cases the warp might be severed at such a point that the course of the current instead of being through such warp from the metallic piece L to the warp beam, and from the latter through the frame back to the lay, might be from the metallic piece L through a portion of the severed warp through the breast beam to complete the circuit,—no attempt being herein made to set forth all of the courses which the electro magnet circuit, when closed by a severed warp, may have, as such circuit will be in part by its shortest path through some metallic part of the loom frame; and the utilization of the metallic frame and parts of the loom as a conductor is merely a practical expedient for the avoidance of some wiring which would be cumbersome.

Inasmuch as it may, more often than otherwise, be desired that the loom shall not be stopped, after a warp has become broken, until the operating parts of the loom shall have moved to some desired and predetermined position, as, for instance, with the lay swung fully back and the other parts in their corresponding positions, an additional circuit comprising the dynamo and the magnetic clutch is provided with a circuit opening and closing controller therefor and operable for maintaining a dynamo circuit through the magnetic clutch even after a dynamo circuit has been established by the shifting of the switch f through the brake magnet,—such further clutch magnet circuit by the properly timed action of the controller being opened so as to leave no circuit closed for the dynamo current through the clutch magnet, at the desired given time, as for instance, when the lay is fully back.

P represents the controller comprising opposite separated metallic parts m, n, insulated from each other at n^2 , and a movable bar o consisting of metallic and insulating sections o^2 , o^3 , to electrically connect, or leave insulated from, each other, accordingly as the bar is in the positions of Figs. 1 or 2, the opposite metallic members m and n of the controller. The wires p and q are in electrical connection with the opposite metallic parts m and n of the controller and in circuit with

the clutch magnet F and with the dynamo; and a simple, economical and practical mode of wiring is to run the wire q from connection with controller part n to the contact e and through the latter to connection with the dynamo connecting wire c^2 ; and to run the wire p from the controller part m to connection with the wire c^2 which is connected with and through the clutch magnet coil and by way of wire c back to the dynamo.

The movable circuit closing and opening bar o of the controller is represented in Figs. 2 and 2^a as operated by a cam s on a rotary shaft v connected to be driven by the worm gearing u with the shaft D of the loom, said cam being so shaped and the motion thereof being so timed that a quick downward and upwardly returning movement will be periodically imparted to the said bar o of the controller to change the relations and establish the conditions perceived in Fig. 1 to those perceived in Fig. 2, in which figures the circuit in which the controller is comprised, in Fig. 1, is closed, the lay being in a forward position while in Fig. 2 the circuit at the controller is indicated as opened, and the lay as in its most rearwardly swung position.

When the stop motion is applied on the loom with conductors for establishing a circuit comprising the dynamo, the clutch magnet and the controller P, additional to the dynamo and magnetic clutch circuit in which the switch f is comprised, as represented in Figs. 1 and 2,—in extension of the idea of means more simply represented in Fig. 3,—it is to be provided that the brake magnet in opposition to the clutch magnet must be of equal, or in any event of no greater, effectiveness than the clutch magnet, for it will be apparent that if a warp breaks at a time when the lay is otherwise than fully back there will be a dynamo current established through the brake magnet during a very short interval that a dynamo current remains also established through the clutch magnet by way of the conductors connected with and included in the controller; and, hence, as is desired, the clutch will not become deenergized, and will not terminate the connection with the driving shaft, to permit the magnetic brake to become effective to stop said shaft until the second path for the dynamo current through the clutch magnet is terminated at the controller after the normal path for such dynamo current through the clutch magnet has, on a warp breaking, been terminated by the opening of the switch f.

I have shown in addition to the transverse insulated strip L located at the rear portion of the lay beam, other similar strips L² and L³ in Fig. 4, as located upon the front of the lay beam and on a lower rear portion of the reed cap; and in Fig. 2 still further of these transverse metallic strips are represented by L⁴ and L⁵ as additionally provided at suitable

points adjacent and crosswise in relation to the warp wires, behind the lay and understood as mounted on, and insulated from, suitable supports therefor other than the lay. 5 These transverse insulated cross strips, rods or wires, cost almost nothing, and it is considered desirable to have an ample number of them at various places between the warp beam and cloth line, each having a connection in the circuit comprising the electro magnet N in substantially the same manner as provided for the connection in such circuit of the particular insulated metallic strip L.

By providing a number of the strips electrically connected in the manner of the one L particularly described and appropriately arranged the best of assurance will be had that no matter where a warp wire breaks nor whether it sags downwardly or snaps in an upward direction,—the electro magnet circuit will by the conductivity of the metallic warp be instantaneously closed.

I claim:—

1. In an electric warp stop-motion for a wire weaving loom, a driving shaft for operating the movable parts of a loom, a driver therefor, and a magnetic device for connecting and disconnecting said shaft with and from the driver therefor, an electric generator, circuit conductors connected with said generator and with said magnetic device, normally closed, and having a circuit closing switch or cut-out, an insulated metallic piece extending transversely of the loom and in relation to the warps,—to be contacted against upon a severing of one thereof,—an electro magnet controlling said cut-out switch, and circuit conductors, having a generator connected therewith, and connected with said electro magnet, and connected with said metallic piece, and with a part of the loom with which the warp wires are in metallic or electrical connection.

2. In an electric warp stop-motion for a wire weaving loom, a driving shaft for operating the movable parts of a loom, a driver therefor, and a magnetic brake operable to stop the said shaft, an electric generator, circuit conductors connected with said generator and with said magnetic brake, normally open, and having a closing switch therefor, an insulated metallic piece extending transversely of the loom and in relation to the warps,—to be contacted against by a severed warp,—an electro magnet controlling said switch for maintaining the brake circuit open, circuit conductors, comprising a generator, connected with said electro magnet, connected with said transverse metallic piece, and with a part of the loom with which the warp wires are in electrical connection.

3. In an electric warp stop-motion, a driving shaft for operating the movable parts of a loom, a driver therefor, a magnetic device for connecting and disconnecting said

shaft and driver, and a magnetic brake operable to stop the said shaft, circuit conductors connected with said magnetic device, circuit conductors connected with said magnetic brake, and a dynamo or generator connected in each of said circuits, the magnetic connecting device circuit being normally closed and the magnetic brake circuit being normally open, a cut out switch, for maintaining the one said circuit closed and the other circuit open, an insulated metallic piece extending transversely of the loom and in relation to the warps, and to be contacted against by a severed warp, an electro magnet for controlling said switch, circuit conductors, comprising a generator, connected with said electro magnet, and connected with said transverse metallic piece and with a part of the loom with which the warp wires are in metallic connection.

4. In an electric warp stop motion, a driving shaft for operating the movable parts of a loom, a driving pulley loosely revoluble relatively thereon, a clutch magnet for connecting and disconnecting said pulley and shaft, a dynamo, circuit conductors oppositely connected with said dynamo and with said clutch magnet, normally closed, and having a circuit closing switch or cut-out, an insulated metallic piece extending transversely of the loom adjacent the run of the warps,—and to be contacted against, by a warp upon a severing thereof,—an electro magnet controlling said cut-out switch, and circuit conductors comprising a generator connected with said electro magnet, and connected with said transverse metallic piece and with a portion of the loom with which the warp wires are in electrical connection.

5. In an electric warp stop motion, a driving shaft, for operating the movable parts of a loom, having a brake disk affixed thereon, driving means for said shaft and a brake magnet mounted on a stationary support adjacent said brake magnet, and relatively to which the latter revolves, an electric generator, circuit conductors connected with said generator and with said brake magnet, normally open, and having a closing switch therefor, an insulated metallic piece extending transversely of the loom and adjacent the warps, an electro magnet controlling said switch, and circuit conductors, comprising a generator, connected with said electro magnet, and connected with said transverse metallic piece and with a part of the loom with which the warp wires are in electrical connection.

6. In an electric warp stop-motion for a wire weaving loom, a driving shaft for operating the movable parts of a loom, a driver therefor, and a magnetic device for connecting and disconnecting said shaft with and from the driver therefor, a metallic lay an electric generator, circuit conductors con-

- 5 connected with said generator and with said magnetic device, normally open, and having a circuit closing switch or cut-out, a metallic piece mounted on the lay and insulated therefrom, and extending transversely of the loom, and to be contacted against by a severed warp, an electro magnet controlling said cut-out switch, and circuit conductors, oppositely in electrical connection with said insulated
- 10 metallic piece and with the metallic beam of the lay, and connected with said electro magnet, and having a generator connected therein.
7. In an electric warp stop motion for a wire weaving loom, a shaft for driving the movable parts of the loom, a driver therefor, and a magnetic device for connecting and disconnecting the driver and said shaft, an electric generator, circuit-conductors connected with said generator and with said magnetic device, having a cut out switch, a circuit opening and closing controller, and conductors connecting it in circuit with the generator and said magnetic connecting device, an electro-magnet controlling said cut out switch and normally open circuit conductors therefor, comprising a generator and adapted to be closed by a severed warp, and means for periodically actuating said controller for opening the said circuit in which it is comprised.
8. In an electric warp stop-motion for a wire weaving loom, a driving shaft for operating the movable parts of a loom, a driver therefor, and a magnetic device for connecting and disconnecting said shaft with and from the driver therefor, an electric generator, circuit conductors connected with said generator and with said magnetic device, normally closed at one place therein, and having a switch or cut-out at such place, a circuit opening and closing controller, and conductors connecting it in circuit with the generator and said magnetic connecting device, an insulated metallic piece extending transversely of the loom,—to be contacted against by a severed warp,—an electro magnet controlling said cut-out switch, circuit conductors,—having a generator connected therewith,—connected with said electro magnet, connected with said metallic pieces, and with a part of the loom with which the warp wires are in metallic or electrical connection, and means for periodically operating said controller for its circuit opening action when the loom lay is in a given required position.
9. In a warp stop motion for a wire weaving loom, a shaft in driving connection with the movable parts of the loom, having a disk affixed thereon, a brake magnet at one side of said disk, and a pulley loosely rotatable on the shaft at the other side of said disk and carrying a clutch magnet, an insulated metallic piece extending transversely of the
- 15 loom to be contacted against upon the severing of a warp wire, a dynamo and an electric conductor connected with said dynamo and with said switch, separated contacts, and a conductor running from one of said contacts to said clutch magnet, and a conductor running from said clutch magnet back to the dynamo, an electric conductor running from the other of said contacts to said brake magnet, and another contact, connected with said brake magnet and with the dynamo, an electro magnet, and an armature therefor engaging the said switch and holding the same on the one of said contacts in the clutch magnet circuit, means for throwing the switch, when released, onto the contact in the brake
- 20 magnet circuit, and circuit conductors, comprising a generator, connected with said electro magnet, connected with said insulated metallic piece, and with a part of the loom with which the warp wires are in metallic or
- 25 electrical connection.
10. In an electric warp stop motion for a wire weaving loom, a driving shaft for operating the movable parts of the loom, a driver therefor, a magnetic device for connecting and disconnecting said shaft and driver, and a magnetic brake operable to stop the said shaft, circuit conductors connected with said magnetic connecting device, circuit conductors connected with said magnetic brake, and
- 30 a dynamo connected in each of said circuits, the magnetic-connecting-device-circuit having a cut out opening at one place therein, and a circuit opening and closing controller comprising separated insulated metallic pieces, and a movable bar consisting of metallic and insulating portions, operable to connect, and also to leave electrically cut out, one of said metallic portions of the controller with and from the other, and conductors connecting said controller in circuit with said generator and said magnetic connecting device, a switch for normally closing the first named cut out opening, and for leaving normally open the magnetic brake circuit, and movable for reversing its relations, an insulated metallic piece extending transversely of the loom and to be contacted against by a severed warp, an electro magnet for controlling said switch, circuit conductors comprising a battery connected with said electro magnet and connected with said insulated metallic piece and with part of the loom with which the warp wires are in metallic connection, and a rotary cam for periodically moving said bar of the controller for cutting-out the magnetic connecting device circuit in which such controller is comprised at a given predetermined time in each operation of the loom.
- 35 11. In an electric warp stop motion for a wire weaving loom, a shaft for driving the movable parts of the loom, a driving pulley

therefor, and a magnetic clutch for connecting and disconnecting said pulley and shaft, a dynamo, circuit conductors connected with said dynamo and with said magnetic clutch, having a cut out switch, an electro magnet having an armature for engaging, and holding said switch in its circuit closing position, and normally open circuit conductors for said

electro magnet comprising a battery, and adapted to be closed by a severed warp. 10
